UNITED STATES PATENT OFFICE.

FRANCIS J. MELVIN, OF OWOSSO, MICHIGAN, ASSIGNOR OF ONE-HALF TO
EDWIN A. GOULD, OF SAME PLACE.

ROAD-CART.

SPECIFICATION forming part of Letters Patent No. 391,060, dated October 16, 1888.

Application filed December 31, 1887. Serial No. 259,524. (No model.)

To all whom it may concern:

Be it known that I, FRANCIS J. MELVIN, of Owosso, in the county of Shiawassee and State of Michigan, have invented a new and useful Improvement in Road-Carts, which improvement is fully set forth in the following specification and accompanying drawings, in which—

Figure I is a sectional side elevation of my improved road-cart. Fig. II is a rear elevation of same, and Fig. III a perspective view showing the manner of attaching the side springs and seat-risers to the cross-bar.

The object of my invention is to construct an improved road-cart which is designed to combine lightness, strength, and durability, with consequent light draft and ease of motion. The advantages obtained are an almost entire freedom from the unpleasant oscillating or rocking motion which has heretofore been inseparable from vehicles of this description, the best attainable balance with the consequent comfort to horse and driver, the greatly-reduced tendency of jolting or "throwing" when passing over crossways or other obstructions, and the increased safety due to the mode of adjusting the load upon the axle.

My invention consists in the peculiar arrangement and relation of the various parts, and will be readily understood by reference to the accompanying drawings, in which—

A represents the seat-riser, secured by clips to the side spring, B, the upper leaf of which is extended forward and hinged on a shackle-bolt, C, to the cross-bar D. By this means of

attachment the seat-riser has a peculiarly easy 35 movement and renders the motion of rising more comfortable than usual in this class of devices. The side springs, B, extend rearwardly and downwardly to a point directly above the axle, where they connect with the 40 cross-spring E, which is supported centrally by the bracket F. The ends of this bracket may be welded or otherwise secured to the axle G. This disposition of the bracket and axle constitutes a truss, by means of which the 45 load is placed near the ends of the axle. The great advantages of this arrangement are manifest. The semicircular dash-board H is attached at one end to the cross-bar D by an eyebolt, the other end being flanged and bolted 50 to the seat-riser at a point perpendicular to the axle. The thills I are rigidly secured to the cross-bar D and axle G by suitable clips.

What I claim as new is—

A road-cart having side springs secured to 55 the seat risers, the upper leaf of said springs extending forwardly and hinged to the cross-bar, in combination with the rear ends of said springs connected with the cross-spring and with the axle and shafts, substantially as herein 60 set forth.

In testimony that I claim the foregoing I have hereunto set my hand, this 28th day of September, 1887, in the presence of witnesses.

FRANCIS J. MELVIN.
